ELECTRIC SWITCH

Lawrence J. Bordelon, San Diego, Calif., assignor
to Consolidated Vultee Aircraft Corporation,
San Diego, Calif., a corporation of Delaware

Application October 25, 1946, Serial No. 705,578

6 Claims. (Cl. 200—106)

1

This invention relates to improvements in electrical switches and more particularly to an electrical switch which is so constructed that it will serve, not only to initiate the actuation of a motor or motors associated in circuit therewith, but will also indicate when devices actuated by said motor or motors have completed the function or movement for which they are designed.

Basically, the switch consists in a spring biased operating element which is so associated with a rocking contact element that the rocking element always tends to return to a neutral, circuit breaking position. To control the return of the operating element there is associated with the operating element a solenoid installed in series with the switch, which is adapted to maintain the rocking contact element in its circuit making position. To permit the proper actuation of the switch it is necessary that there be placed in circuit with it limit switches or similar circuit breaking devices. Thus, when the elements driven by the motors actuated by the switches have performed their function they inactivate the limit switches, break the circuit, withdraw the solenoid core and permit the operating element to be returned to its neutral position. Therefore, the necessity for the manual throwing of the switch to its circuit breaking position is precluded and the return of the operating element gives a visual indication of the satisfactory completion of the operation. Further, the operating element is automatically retained in its circuit making position and it is no longer necessary to hold the switch in its circuit making position until the desired sequence of action initiated by the throwing of the switch is accomplished.

One object of this invention is to provide an electrical switch which is so constructed that it will automatically return to its neutral, circuit breaking position upon the completion of an operation for which it has been thrown.

Another object of the invention is the provision of a switch, the position of whose operating element or throw will indicate the proper completion of a predetermined action by a mechanism associated with the switch.

A further object of this invention is the provision of an electrical switch which has embodied therein means adapted to indicate a failure in the circuit or mechanism associated with said switch.

An additional object of this invention is the provision of an electrical switch which is capable of being both automatically and mechanically returned from its circuit making position to its neutral or circuit breaking position.

2

A further object of the invention is the provision of an electrical switch which, although having means embodied therein to accomplish its automatic return to the circuit breaking position, need not be held in position by manual means in performing its circuit making function.

Other objects and advantages of the invention will be made apparent by a consideration of the specification and the accompanying drawings, in which:

Figure 1 is a side elevational view, partly in section, showing the switch in its circuit making position;

Figure 2 is an end elevational view, partly in section, shown in its circuit breaking or inoperative position;

Figure 3 is a perspective view showing the configuration of the rocking contact element; and

Figure 4 is a schematic view showing the switch elements and a typical circuit in which they are utilized.

There is shown in the drawings a preferred embodiment of the switch 10 which includes a generally rectangular housing 11 having ears 12 formed integrally therewith depending from its lower edge which are crimped over to retain a base or closure member 13 thereupon. Closure member 13 is made of insulating or non-conductive material and has cut or otherwise formed therein at opposite ends slots 14 adapted to receive terminal members 15 and 16. The upper ends of terminal members 15 and 16 are bent over so as to provide efficient contact surfaces 17 and 18. Terminal members 15 and 16 are provided with binding screws 19 to permit the attachment thereto of conductors 20.

Located within the housing 11 in such a manner that opposite ends thereof are adapted to be imposed upon contact points 17 and 18 for circuit making action is a rocking contact member 21 which is mounted upon a bracket 22 whose vertical sides 23 have orifices therein adapted to receive ears 24 projecting from the sides of the rocking contact member 21 at its mid-portion.

The rocking contact member 21, which is made of conductive material, comprises a slightly bent plate 25 having a rectangular orifice 26 which is traversed by a band 27 of material formed integrally with the plate 25. The band 27 is so formed that it presents an arcuate concavity 28 in which there is cut a longitudinal slot 30 for a purpose to be hereinafter shown. As previously indicated ears 24 project from the opposite sides of bent plate 25 at substantially the mid-point of the plate. Thus, the rocking contact member is

susceptible of being actuated upon the bracket 22 in such a manner that its opposite ends may be alternately brought into circuit making contact with contact points 17 and 18.

A throw or operating element 29 which is adapted to cause the displacement of the rocking contact element 21 from its neutral to its circuit making positions is mounted in an annular flange 31 which defines a hole 32 formed at substantially the mid-point of the top of housing 11. Operating element 29 comprises a grip portion 33 which has formed integrally therewith a ball base 34 which seats in annular flange 31 and is retained therein by means of switch mounting plate 35 fastened to the housing 11, as by means of rivets 36 and which has formed therein an annular flange 37 adapted to cooperate with the upper portion of ball base 34 and retain it in position on the top of housing 11. There is formed within both the ball base 34 and the grip portion 33 an axial hole 38 in which is seated an expansion spring 39 which biases against the end of a plunger or rod 41 formed of non-conductive material and adapted to ride within the arcuate concavity 28 formed in the rocking contact member 21. The displacement of the operating element 29 causes the rod 41 to be moved along the surface of the rocking contact member 21 thus causing the rocking contact member 21 to be tilted on its bracket support 22 and bringing either end of the rocking contact member 21 to bear upon either of contact points 17 or 18.

When the rocking contact member 21 is displaced from its neutral position into either of its circuit making positions by the movement of operating element 29 the spring 39 is compressed by the upward travel of rod 41 and there is a tendency for the spring to return operating element 29 and its associated rocking contact member 21 to its neutral position.

To prevent this displacement during a prolonged operation and yet permit the switch to break the circuit in which it is located automatically, there is provided a solenoid 42 which is mounted on closure member 13 by means of rivets or similar fastening devices 43 which pass through upper flange 44 of the solenoid 42 and hold it immediately below rocking contact member 21. The solenoid 42 comprises a magnetic coil 45 of conventional type which is wired in series with the switch and through the center of which runs a core 46 which is adapted to be displaced upwardly upon the making of the circuit by the throwing of the switch 10. The lower end of core 46 has formed thereupon an integral flange 47 on which is seated one end of an expansion spring 48, the upper end of said spring being biased against the bottom flange 49 of solenoid 42. Therefore, when the circuit is broken by the action of associated limit switches or similar devices and the coil 45 of the solenoid 42 is no longer activated, the spring 48 will retract the core 46 into its inactive position within the coil 45.

There is formed on the upper end of the core 46 of solenoid 42 a blade or detent portion 51 having a concavity 52 formed in its tip and adapted to project through an aperture 40 in base or closure member 13 and longitudinal slot 30 in rocking contact member 21. When the throwing of operating element 29 causes the rocking contact element 21 to make the circuit with one of the contact points 17 or 18, the blade portion 51 is longitudinally displaced through the slot 30 in rocking contact member 21. The edge of blade 51 will be brought into contact with the

end of plunger or rod 41 (as shown in Fig. 1) and will retain the operating element 29 in its circuit making position so that the end of rocking contact member 21 will be kept in circuit making position with contact point 17. In order to provide for the conduction of electricity through rocking contact member 21 a lead 53 is extended from the upper portion of the coil and soldered or otherwise affixed to said rocking contact member.

In Figure 4 there is shown a typical circuit in which a switch of the above described type could be efficiently utilized. The switch 10 is placed in circuit with limit switches 54 by means of conductors 55. Conductors 55 connect the limit switches 54 to the motors 56 which are grounded at 57. A source of power or battery 58 powers the circuit and a lead 59 is shown running therefrom into solenoid coil 45. Motor driven actuators 60 are adapted to contact limit switches 54 at the end of their travel so that the circuit will be broken and the switch 10 returned to its neutral or circuit breaking position upon the inactivation of the solenoid 42.

The switch 10, in addition to holding the circuit closed during an operational sequence and then breaking the circuit to indicate the proper completion of said operational circuit by the return of switch throw 29 to its neutral position, also serves a vital protective function. In the circuit shown in Figure 4, an inoperative limit switch would prevent the actuation of the motors since the switch 10 controlling the circuit would not remain in its circuit making position because the circuit would not be made through the solenoid and the retaining blade or detent would not be extended against the switch throw. Therefore, an immediate indication of an inoperative circuit would be presented.

There is thus provided a switch which will automatically be retained in circuit making position until the completion of an operational sequence, and which will return to its neutral, circuit breaking position to indicate visually to the operator the completion of said sequence. The switch also possesses a safety feature in that it cannot be held automatically in circuit making position if the failure of associated circuit breaking devices should occur.

The embodiment described above is merely a preferred embodiment of the invention utilized to display the manner of construction and mode of operation of the device and it is, of course, obvious that changes could be made in details of construction which would still fall within the scope of the appended claims.

I claim:

1. In an electric switch, a housing, a closure means for said housing, a plurality of stationary contact members supported by said closure means, a contact member for individually engaging said stationary contact members, means for pivotally mounting said movable contact member, spring biased means exerting its force normally to maintain said movable contact member in circuit breaking position, an actuating member movably supported on said housing, adapted to control said spring biased means for moving said movable contact member into its circuit making and circuit breaking positions, electro-magnetically operated means in series circuit with said movable contact member supported by said closure means and cooperating with said spring biased means to maintain said movable contact member in circuit making position.

2. In an electric switch having a housing and closure means therefor, stationary contact means supported by said closure means, a movable contact member for engaging said stationary contact means, mounting means provided on said closure means for pivotally mounting said movable contact member, spring biased means engageable with said movable contact member providing a force normally to maintain said movable contact member in circuit breaking position, an actuating member movably supported on said housing adapted to control said spring biased means for moving said movable contact member into its circuit making and circuit breaking positions, electro-magnetically operated means in series circuit with said movable contact member supported by said closure means and engageable with said spring biased means to maintain said movable contact member in circuit making position.

3. In an electric switch, a housing, a closure means for said housing, a plurality of stationary contact means supported by said closure means, a movable contact member for individually engaging said stationary contact members, mounting means carried by said closure means for pivotally mounting said movable contact member at a point substantially centrally thereof, spring biased means engageable with said movable contact member providing a force normally to maintain said movable contact member in circuit breaking position, an actuating member pivotally supported on said housing adapted to carry said spring biased means for movement bodily thereof to actuate said movable contact member into its circuit making and circuit breaking positions, electro-magnetically operated means supported by said closure means and cooperating with said spring biased means to maintain said movable contact member in circuit making position, said electro-magnetically operated means comprising a solenoid coil in series circuit with said movable contact member and a movable means actuatable upon energization of said coil to move into engagement with said spring biased means when the latter has operated said movable contact member into circuit making position.

4. In an electric switch having a housing and a closure means therefor, a plurality of stationary contact members supported by said closure means, a moveable elongated contact member for successively engaging said stationary contact members, said movable contact member being provided with an opening therethrough, mounting means carried by said closure means for pivotally mounting said contact member at a point substantially centrally thereof, spring biased means engageable with said movable contact member providing a force normally to maintain said movable contact member in circuit breaking position, a manually operable actuating member pivotally supported by said housing adapted to carry said spring biased means for movement bodily thereof to actuate said movable contact member into its circuit making and circuit breaking positions, electro-magnetically operated latch means supported by said closure means and cooperating with said spring biased means to maintain said movable contact member in circuit making position, said electro-magnetically operated latch means comprising a solenoid coil in series circuit with said movable contact, a movable core actuatable upon energization of said coil and disposed on the side of said movable contact member opposite to said spring biased means, and

5. In an electric switch, a housing, an insulating closure means for said housing having an opening therethrough, a pair of stationary contact members supported by said closure means, a movable elongated contact member for alternately engaging said stationary contact members, said movable contact member being provided with an opening aligned with said opening in said closure means, mounting means carried by said closure means for pivotally mounting said contact member for movement about its center, wiring terminal means carried by said stationary contact members, a manually operable actuating member pivotally supported by said housing, spring biased means carried by said actuating member and engageable with said movable contact member for pivoting it into circuit making position upon operation of said actuating member and for automatically returning it to circuit breaking position, electro-magnetically operated latch means supported by said closure means and cooperating with said spring biased means to maintain said movable contact member in circuit making position, said electro-magnetically operated latch means comprising a solenoid coil in series circuit with said movable contact member supported exteriorly of said closure means, a movable core actuatable upon energization of said coil and disposed on the side of the movable contact member opposite to said spring biased means, and detent means mounted on said core and adapted to be moved by said core to move through the opening in said movable contact member to engage said spring biased means when the latter has been moved by the manual actuating member to move said movable contact member into circuit making position.

6. In an electric switch, a housing, an insulating closure means for said housing having an opening therethrough, a pair of stationary contact members supported by said closure means, a movable elongated contact member for alternately engaging said stationary contact members, said movable contact member being provided with an opening aligned with said opening in said closure means, mounting means carried by said closure means for mounting said contact member for rocking movement, said stationary contact members extending to the exterior of the housing and carrying wiring terminal means on said exterior portion, a manually operable actuating member pivotally supported by said housing, spring biased means operatively carried by said actuating member and engageable with said movable contact member for moving it into circuit making position upon operation of said actuating member and for automatically returning it to circuit breaking position, electro-magnetically operated latch means supported by said closure means and cooperating with said spring biased means to maintain said movable contact member in circuit making position, said electro-magnetically operated latch means comprising a solenoid coil in series circuit with said movable contact member supported exteriorly of said closure means and adapted to be energized on movement of said movable contact in circuit making position, a movable core actuatable upon energization of said coil and dis-

posed on the side of the movable contact member opposite to said spring biased means, and detent means mounted on said core and adapted to be moved by said core to move through the opening in said movable contact member to engage said spring biased means when the latter has been moved by the manual actuating member to move said movable contact member into circuit making position.
